United States Patent Office.

NELSON JOHNSON, OF JASPER, NEW YORK.

Letters Patent No. 96,009, dated October 19, 1869.

IMPROVEMENT IN SAW-SWAGE.

The Schedule referred to in these Letters Patent and making part of the same.

To all whom it may concern:

Be it known that I, NELSON JOHNSON, of Jasper, in the county of Steuben, and in the State of New York, have invented certain new and useful improvements in Swages; and do hereby declare that the following is a full, clear, and exact description thereof, reference being had to the accompanying drawings, and to the letters of reference marked thereon, making a part of this specification.

The nature of my invention consists in the construction of a swage, for sharpening and spreading the points of saw-teeth.

Figure 1 is a perspective of my invention.

Figure 2 is section view of the same.

Letter A represents the stock of my swage, which consists of a steel bar, and which has a tapering opening made in its end, which extends backward some distance, where it runs into a slot, made entirely through the side, and extending at right angles with it.

In this tapering hole there is placed the swage-pin B, which extends to some distance out beyond the end of the stock.

At the back end there is a slot cut through, in which there is placed a tapering wedge, C, which holds the pin securely and firmly in its place.

Pivoted on the top of the stock, there is a flat metal plate, D, which acts as a key to hold the wedge in its place, and to prevent its coming out.

In the front end of the stock A there is a number of small openings made, which slant inward, until they strike the swage-pin B.

These openings are of different sizes, so as to accommodate different-sized teeth, and should form a perfect joint against the side of the pin, so that the teeth can be given a razor-edge.

Upon the end of the swage-pin B there is placed the adjustable gauge E, which consists of a flat metal

plate, in which there is cut an elongated slot, so that it can be turned freely in any direction, and can be moved up and down on the bolt which secures it to the pin.

In sawing rough lumber, it is very often necessary to bring the points of the saw-teeth down somewhat, so as to strengthen them, and prevent their being broken.

In doing this, it is very necessary that each separate tooth should receive just the same pitch, which it is impossible to give, unless there is some guide to direct you.

This gauge is adjusted to the proper position, and is then securely fastened there, by the means of the bolt or screw.

As the teeth are placed in these small bevelled openings, the gauge will regulate the angle at which the stock is to be held, and thus each tooth will be upon exactly the same pitch.

Having thus described my invention,

What I claim, and desire to secure by Letters Patent, is—

1. The adjustable gauge E, upon the end of the swage-pin, for the purpose of regulating the pitch of the teeth, substantially as set forth.

2. The key D, when used to hold the wedge C in its place, substantially as set forth and described.

3. The arrangement of the block A, with a slot in its end and side, pin B, wedge C, and key D, the several parts constructed and operated as specified.

In testimony that I claim the foregoing, I have hereunto set my hand, this 12th day of May, 1869.

NELSON JOHNSON.
